ABSTRACT

Wall structure for exhibition purposes having a panel-shaped element with a profile frame with cover layers enclosing a filler layer. The frame is closed as a square box profile with a circular longitudinal slot therein for mounting purpose.

WALL STRUCTURES

This invention relates to a wall structure especially for exhibition structures and cases, with a panel-shaped element containing a profile frame provided on both sides with cover layers which enclose a filling layer. The profile frame may be composed of light metal.

In exhibitions or similar events, special walls, boxes or separate spaces for exhibited objects, discussions, etc., are required in halls or even outdoors. The erection of such walls is accomplished in a known manner by means of prefabricated wall surfaces or wall surfaces that have been fitted right on location spot which are mounted on special frames, structures or similar elements. This method of construction however is cumbersome, costly and time consuming.

It is an object of the invention to simplify the erection of such walls and thus to provide saving in time and money and therefore making it feasible.

According to the invention, it is a further object to provide the profile frame developed as a closed frame with a preferably square box section having on its outside a circular longitudinal slot for the purpose of mounting which has been broadened at the corners of the frame.

This wall structure according to the invention, offers many possibilities for mounting. One of these is distinguished by the fact that for the connection of the panel-shaped elements, connecting devices have been provided which in each instance contain two pressure plates of an approximately square base surface, and having a screw to pull the pressure plates together. An annular elastic element surrounds the screw and is arranged between the pressure plates, and four clamping cams are arranged in a plane running between the pressure plates, which cams protruding with conical feet into the area of recesses in the surfaces of the two-pressure plates facing each other, lie between the elastic element and the corresponding bevels of the recess and which have preferably circular disk-shaped clamping plates outside the area of the pressure plates. The plates are dimensioned so that they can be slid through the width of the longitudinal slot in the profile frame into said frame while the cross sectional dimensions of the connecting elements between the feet and the clamping plate have been harmonized with the width of the circular longitudinal slot. One could call this arrangement a cubic connecting device.

The assembly is accomplished in such a way that a circular clamping plate of the clamping block is inserted in the enlarged slot of the profile frame and it is pushed forward laterally to such a point that the clamping plate will be located below the narrow slot. Logically, the remaining plates are then put together. By pulling the pressure plates together by means of the screws, all elements that have been put together will be firmly braced and securely held.

Two plate elements abutting against each other on their front sides are connected according to another embodiment of the invention, characterized by the fact that for a front side connection of panel-shaped elements, coupling elements have been provided which in each instance contain a bar-shaped coupling element with a square cross section permitting the said coupling element to slide into the profile frames of the panel-shaped elements that are to be connected by the en-

largements of the longitudinal slots, as well as at least two clamping screws to brace in the profile frames, the coupling element slid into the said profile frames.

Similarly the panel-shaped elements can be provided with feet. The foot elements likewise developed as a bar-shaped body with a square cross section have been harmonized in such a manner that they can be slid into the profile frame. Bracing is accomplished by means of a screw arranged in the body of the foot element.

10 In order to be able to compensate for any unevenness, an adjusting screw with a round head has been arranged in the lower end of the foot. Special plate-like supporting surfaces will prevent foot marks on sensitive floors and will assure a safe stand of the panel-like elements put together to constitute a wall.

15 A crack developed between two sides of the profile frame lying one beside the other will be filled by a hollow molding made of some elastic raw material which has longitudinal bars on two opposite sides, the width of which has been harmonized with the slot of the profile frame and is held thereon.

20 The panel-shaped elements can also serve as supports for light fixtures or can be developed as a lamp directly.

25 Further objects will be apparent from the following description when considered in connection with the accompanying drawings in which;

30 FIG. 1 is a front view of a section of the wall partly in section,

35 FIG. 2 is a cross-section of the cubic connecting device,

40 FIG. 3 is a section taken on line III—III of FIG. 1, in the direction of the arrows,

45 FIG. 4 is a perspective view of the filling molding for a joint,

50 FIG. 5 is a perspective view of a coupling element,

55 FIG. 6 is a side view of a foot element, and

60 FIG. 7 is a sectional view of a foot-plate.

A panel-shaped element 1 has a closed frame 1a, whose preferably square box profile has a slot 1b extending along the outer periphery of the frame and which has been broadened at the corners of the frame and has been provided on both sides with double plates 1c which enclose a filler layer 1d.

The connection of the elements 1 with a wall 2 is accomplished by means of a cubic connection arrangement 3, FIGS. 1 to 3. It consists of two pressure plates

50 3a of approximately square base surface, of a screw 4 for pulling the pressure plates 3a together, an annular elastic element 5 surrounding the screw 4 and arranged

55 between the pressure plates 3a, and four clamping cams 6 arranged in a plane running between the pressure plates 3a and having conical feet 6a which abut against corresponding beveled surfaces 3b of a recess provided on the sides of the pressure plates 3a opposite each other. Furthermore the clamping cams 6 preferably have circular clamping plates 6b protruding

60 from the approximately cubic contour of the pressure plates 3a held together by the screw 4, whereby the diameter of the connecting element 6c of the clamping

65 cams 6 has been harmonized with the slot 1b extending about the outer periphery of the profile frame 1a. The broadened portions 1e of the slot provided at the edges of the frame 1a makes possible the insertion of the clamping cams 6 into the profile frames 1a. By tighten-

ing the screw 4, the panel elements 1 connected with one another by means of the clamping cams 6, are firmly held together.

The spaces 7 resulting during the assembly of the panel elements 1 in a wall 2 are filled by means of a hollow molding 8 with longitudinal bars or ridges 8a attached to opposite sides thereof, said molding being made preferably of an elastic material and the width of the bars 8a harmonized with slot 1b of the profile frame and resting in said frame, FIG. 4.

For the connection of two elements 1 abutting against each other at the front sides, there is provided a coupling element 9, FIG. 5, and this bar-shaped coupling element 9, has a square body provided with a groove 9a harmonized with the slot 1e and the inside dimensions of the profile frame 1a, and is slid in each time about half way into the profile frames 1a of two abutting elements 1 and is braced by means of clamping screws 10 provided in the coupling element 9.

The support of one element 1 in relation to a floor surface is accomplished by means of feet 11, FIG. 6. The bar-shaped body of one foot element 11 whose square cross-section has likewise been provided with the inside dimensions of the profile frame 1a, is slid into the broadened slot 1e of the profile frame 1a and is braced by means of a clamping screw 12 arranged in a groove-like recess 11a.

Unevennesses in a floor surface can be compensated for by means of compensating screw 13 provided in the lower part of foot 11. In order to avoid as much as possible, the foot marks in a floor and in order to achieve a better seating of the feet 11, plate-like supporting surfaces 14, FIG. 7, are used, whereby a ball-joint-like connection between foot 11 and supporting surface 14 is created by the countersunk portion or bolt 14a in the supporting surface 14 and by the round head of the adjusting screw or bolt 13.

In another advantageous and decorative development of the invention, one can also mount light fixtures, shelves or similar devices on the profile frame 1a.

We claim:

1. Wall structure comprising interconnected panel-shaped elements each including hollow frame elements defining a closed frame, each of said frame elements

45

being square in cross-section and having a continuous longitudinal slot in its outer wall, and each said slot being enlarged at each corner of said frame, connecting means for interconnecting said panel-shaped elements, 5 together comprising a pair of substantially rectangular plates, a screw fastener for securing said plates together, an annular elastic element located between said plates and surrounding said fastener, a cam element located between said plates and extending outwardly of each of the four sides of said plates, each said cam element including a conical element in mating engagement with corresponding conical recess sections provided in said plates, said conical elements also contacting said elastic element, each said cam element 10 further including a clamping disc extending outwardly of said pressure plates, and a connecting element between each said disc and each said conical element, each said disc being insertable through an enlarged slot of one of said frame elements so as to lie behind the 15 outer wall thereof after being slid along the longitudinal slot thereof.

2. Wall structure according to claim 1, in which foot elements are provided for erection of said panel-shaped elements, said foot elements each having a bar-shaped body with a square cross-section permitting the partial insertion of said body into the enlarged slot of said frame elements, and at least one clamping screw for bracing said inserted bar-shaped body.

3. Wall structure according to claim 1 wherein foot elements are provided which have a bar-shaped body with a square cross-section permitting the partial insertion of said body into the enlarged slot of said frame elements of the panel-shaped element and at least one clamping screw for bracing said inserted bar-shaped body, and said bar-shaped body having supporting surfaces at one end which can be longitudinally adjusted by means of a screw.

4. Wall structure according to claim 1, in which a hollow molding is provided for the filling of the joints between said interconnected frames, said hollow molding being composed of an elastic material which has longitudinal bars provided on opposite sides at a width permitting its insertion into the longitudinal slot in said frame elements.
